UNITED STATES PATENT OFFICE.

ALBERT N. NORRIS, OF RUSHVILLE, INDIANA.

CULTIVATOR.

SPECIFICATION forming part of Letters Patent No. 272,080, dated February 18, 1883.

Application filed September 22, 1882. (No model.)

To all whom it may concern:

Be it known that I, ALBERT N. NORRIS, a resident of Rushville, in the county of Rush and State of Indiana, have invented a new and useful Improvement in Cultivators, of which the following is a specification, having reference to the accompanying drawings.

My invention relates to that class of cultivators in which the frame consists of laterally movable wings carrying cultivator-hoes hinged thereto, said wings being jointed at one end to a central draft-beam and capable of lateral adjustment at the other end, and in which an adjustable gage governs the depth to which the hoes may enter the earth.

The object of my invention is to firmly sustain the cultivator-hoes against lateral strain.

My invention consists in the means used to accomplish the above-mentioned object, which means are hereinafter clearly shown and described, and particularly pointed out in the claim.

The accompanying drawings illustrate my invention.

25. Figure 1 is an elevation. Fig. 2 is a plan. Fig. 3 is an elevation on an enlarged scale of one of the hoe-supports. Fig. 4 is a similar section of the same. Fig. 5 is a plan on an enlarged scale of the wing-adjusting device. 30 Fig. 6 is a vertical section.

Like letters refer to the same parts in the several figures.

To a central draft-beam, *a*, are hinged side wings, *b b*, in the manner usual in this class of implements. Mounted upon the rear end of beam *a* is a segmental gear, *c*, the hub of which forms journals which rest in bearings in plates *d* and *e*. Plate *d* is provided with two upwardly-projecting lugs, *f* and *g*, which serve as supports for plate *e*, and also for bearings against which racks *h* and *i* slide. Racks *h* and *i* engage the gear *c*, and are extended to form arms which are pivoted to wings *b b*, as shown. To the center of gear *c* one end of a vertical shaft, *j*, is secured, to the upper end of which a crank, *k*, is attached in such manner that its outer end may be raised sufficiently to clear the projections in a notched segmental frame, *l*, which is attached to and between the plow-handles *m*. Frame *l* is a casting of iron having a notched segment, *n*, a cross-bar, *o*, forming a bearing for the upper end of shaft *j*,

centrally located in relation to said segment, and flanges *p*, by which it is secured to the plow-handles *m*, the whole arrangement being such that wings *b b* are simultaneously swung from or toward the central beam by means of the crank *k*, partially revolving shaft *j* and gear *c*, and thereby moving racks *h* and *i*. The tendency of wings *b* to draw together toward the central beam is resisted and prevented by crank *k* engaging one of the notches in frame *l*.

The draft attachment and depth-gage consists of two brackets, *r*, permanently pivoted to the draft-beam just in front of the wings *b*, and adjustably secured to the front end of the beam by means of a bolt passing through a slot, *s*, in said brackets. Brackets *r* are adapted to receive between them, at their lower ends, below the beam, a friction-wheel, *t*, and are also provided with a series of holes, *y*, above the beam, forming a clevis for the reception of the draft-hook *u*.

The hoes are attached to the under side of the wings and center beam by means of a plate, *v*, to which they are hinged between lugs *x*, and are prevented from swinging by a wooden break-pin passing through lugs *y* and the hoe-shank. In order that the hoes may swing easily when they meet an obstruction sufficient to break the pins, it is necessary that they should fit somewhat loosely between the lugs forming the hinge and between those forming the break-pin support, and they are then liable to twist over more or less sidewise. To correct this difficulty, I provide on plate *v* an additional pair of narrow lugs, *w*, which are centrally located between the hinge and the break-pin supports. Said lugs are made to fit closely to the shank of the hoe, so as to support it against lateral strain.

I claim as my invention—

In a cultivator, the combination, with plate *v*, provided with hinge-lugs *x* and break-pin lugs *y*, adapted to fit loosely over the hoe-shank, of lugs *w*, located between said hinge-lugs and break-pin lugs, and adapted to embrace and fit closely over the hoe-shank, in the manner shown and described, for the purpose set forth.

ALBERT N. NORRIS.
